UNITED STATES PATENT OFFICE.

OATMAN H. TANNER, OF DONIPHAN, MISSOURI, ASSIGNOR OF ONE-HALF TO C. E. WHITE, OF DONIPHAN, MISSOURI.

WRENCH.

Application filed May 18, 1922. Serial No. 561,907.

To all whom it may concern:

Be it known that I, OATMAN H. TANNER, a citizen of the United States, residing at Doniphan, in the county of Ripley and State 5 of Missouri, have invented certain new and useful Improvements in Wrenches; and I do hereby declare the following to be a full, clear, and exact description of the invention, such as will enable others skilled in 10 the art to which it appertains to make and use the same:

The present invention relates to wrenches, and aims to provide a novel and improved wrench device for tightening and loosening 15 bolts, nuts, and screws, in inaccessible or cramped places, such as in an automobile engine and transmission mechanism.

Another object of the invention is the provision of a wrench mechanism which can 20 extend around an obstruction and so constructed and operable that the bolt or screw can be conveniently rotated.

A further object is the provision of such 25 a wrench comprising a novel assemblage and construction of the component elements, to render the device practical and efficient for the intended purposes.

With the foregoing and other objects in 30 view, which will be apparent as the description proceeds, the invention resides in the construction and arrangement of parts, as hereinafter described and claimed, it being understood that changes can be made within the scope of what is claimed, without departing from the spirit of the invention.

35 The invention is illustrated in the accompanying drawings, wherein—

Figure 1 is a plan view of the improved wrench.

40 Fig. 2 is an opposite plan view thereof. Fig. 3 is an edge elevation of the device. Fig. 4 is a front end view of the device. Fig. 5 is a sectional detail on the line 5—5 of Fig. 2.

45 In carrying out the invention, there is provided a yoke 7, bent from a rod, and comprising the frame of the wrench to be disposed around or astride an obstruction. One end portion of said yoke is bent at an angle 50 and back to provide an outstanding handle 8 for holding the yoke or frame, and a head 9 is secured to the opposite terminal of the yoke.

55 The bolt or screw engaging member 10 is assembled with the head 9, and, as shown,

has a socket for engaging the head of the bolt or screw or a nut thereon. The member 10 has a reduced shank or stem 11 engaging through a worm wheel 12 disposed in a recess 13 in the outer side of the head 9, and the member 10 projects outwardly from said wheel and head, in a direction opposite to the handle 8. Thus, the handle 8 projects from one end of the yoke or frame to be conveniently held in one hand, while the member 10 projects in an opposite direction from the opposite end of the yoke, to engage the bolt or screw. The shank or stem 11 is preferably of square or angular section, so that the member 10 and wheel 12 60 turn as a unit, and a collar 14 is fitted on said stem within an opening 15 in the head 9 concentric with and smaller in diameter than the recess 13. Anti-frictional rollers 16 are disposed between the collar 14 65 and the periphery of the opening 15, thereby mounting the wheel 12 and member 10 for free rotation. A retaining disk 17 is secured to the end of the stem 11, by means of a screw 18, clamping the collar 14 between said disk and wheel 12. Said disk 17 overlaps the rollers 16 and the inner 70 side of the head 9, to retain said rollers in the opening 15, and to also hold the wheel 12 and member 10 assembled with the head. 75 The wheel 12 covers the opening 15 at one side and the disk 17 covers said opening at the opposite side, with the rollers 16 located between and abutting said wheel and disk.

80 The operating means includes a shaft 19 disposed at one side of the outer arm of the yoke 7 parallel therewith, and journaled in outstanding lugs or bearings 20 with which the head 9 is provided at one side of the recess 13, and a worm 21 is secured on the 85 shaft between said bearings and meshes with the worm wheel 12. The opposite extremity of the shaft 19 is journaled in one flange of an angular bearing bracket 22 which is secured to the outer arm and intermediate 90 portion of the yoke 7, and a crank shaft 23 is disposed parallel with said intermediate portion of the yoke and has its outer terminal journaled in the other flange of the bracket 22. The adjacent ends of shafts 19 95 and 23 are operatively connected by bevel gears 24 secured thereon and meshing with one another. The shaft 23 is journaled through a bearing 25 secured to the inner arm of the yoke, and said shaft has a hand 100

crank 26 at its inner end to be conveniently rotated by one hand while the other hand holds the handle 8.

The yoke 7 and operating means can thus 5 extend partly around or across an obstruction which prevents direct access to the bolt or screw, and the bolt or screw engaging member 10 can thus be conveniently applied to the bolt or screw, and the crank 26 rotated 10 for rotating the shaft 19. The worm 21 will rotate the wheel 12 and the member 10 with considerably increased power, due to the gear ratio. The device can thus be used 15 for tightening or loosening bolts and screws in inaccessible places or behind an obstruction on which the yoke 7 can be placed.

Having thus described the invention, what is claimed as new is:—

1. A wrench comprising a yoke to extend 20 partly around an obstruction and having a handle at the terminal of one of its arms, a head carried by the terminal of the other arm, a bolt or screw engaging member mounted for rotation in said head, a worm 25 wheel rotatable with said member, a shaft extending along the second named arm, another shaft extending along the intermediate portion of the yoke, gears connecting the adjacent ends of said shafts, a worm on the

first named shaft meshing with said worm 30 wheel, said shafts being located in a plane spaced from and parallel with the plane of said yoke, bearings carried by said yoke and head and extending to one side and having the shafts journaled therein, and a crank 35 carried by the second named shaft at that end of said shaft opposite to the first named shaft.

2. A wrench comprising a frame having a head, said head having a recess at one side 40 and an opening of smaller diameter at the opposite side, a wheel in said recess disposed across said opening, a bolt or screw engaging member having a stem engaging through said wheel to turn therewith, a disk secured to the end of the stem and extending across said opening opposite to the wheel, means within said opening around said stem for mounting the stem for rotary movement in the head, and operating means connected to 45 said wheel.

In testimony whereof I have signed my name to this specification in the presence of two subscribing witnesses.

O. H. TANNER.
